(57) **CLAIM**

The ornamental design for a stroller hook, as shown and described.

DESCRIPTION

FIG. 1 is a top front isometric view of a first embodiment of a new, original and ornamental design for a stroller hook.

FIG. 2 is a left side elevational view thereof.

FIG. 3 is a front elevational view thereof.

FIG. 4 is a right side elevational view thereof.

FIG. 5 is a rear elevational view thereof.

FIG. 6 is a top plan view thereof; and,

FIG. 7 is a bottom plan view thereof.

The stitching portions shown in broken dash lines in FIGS. 1-2, 4 and 6-7 form no part of the claimed design.

1 Claim, 6 Drawing Sheets

FIG. 1

FIG. 2

FIG. 3

FIG. 4

FIG. 5
